UNITED STATES PATENT OFFICE.

GASTON BOISSONNAULT, OF NEW YORK, N. Y., ASSIGNOR TO MICROPHO-DETECTOR CO., INC., OF NEW YORK, N. Y., A CORPORATION OF NEW YORK.

TELEPHONE INSTRUMENT.

1,234,613.

Specification of Letters Patent. Patented July 24, 1917.

Application filed December 6, 1916. Serial No. 135,326.

To all whom it may concern:

Be it known that I, GASTON BOISSONNAULT, a subject of the King of Great Britain, residing at New York city, in the 5 county and State of New York, have invented certain new and useful Improvements in Telephone Instruments, of which the following is a specification.

My invention relates to telephone instruments, particularly telephone transmitters and it consists in so constructing and arranging the elements which make up the instrument that its adjustment may be conveniently accomplished, preferably without 15 opening the case.

Figure 1 is a central vertical sectional view of a transmitter embodying my invention.

Fig. 2 is a face view of the instrument, 20 with the cover, the diaphragm and the carbon balls removed.

Fig. 3 is a face view of the rear side of the instrument, showing also the lead wires.

A demand has arisen in the art for a very 25 sensitive instrument and a number of devices intended to meet that demand have been devised.

Such an instrument requires an exceedingly delicate adjustment. The carbon 30 block, generally used to support the granular or ball carbon, must be so adjusted as to approach the diaphragm as closely as possible, but not so close that the vibration of the diaphragm will cause it to make contact with the block, since the contact should be with the granular or ball carbon and contact with the block itself will interfere with that sensitive variation of the current which is necessary for the best results. At the 35 same time said block and diaphragm should be so close that the granular or ball carbon will be retained in its appropriate position.

Heretofore, adjustment has been secured by opening the case and placing one or more 45 disks of mica between the block and its support, but that method is faulty in that it requires considerable time and, in replacing the cover or other parts, an adjustment once satisfactory is liable to be disturbed. Again, 50 for very sensitive instruments carbon blocks

with a series of depressions have been used, each depression filled or partly filled with carbon balls. But to secure good results with such apparatus, each depression should be occupied by the same number of carbon 55 balls and the adjustment of such series, when accomplished, as it must be, by the adjustment of the carbon block, or by changing the number of balls in each recess, is a matter of much difficulty. 60

To meet the difficulty and render a more perfect adjustment possible and at the same time more easily and economically accomplished, I have devised an instrument in which a single depression is provided with 65 a carbon pencil or post located behind the space occupied by the carbon balls and so arranged that it may be advanced or drawn back independently of any movement of the block, to cause the carbon balls in front of 70 it to press more tightly or loosely against the diaphragm, to give the desired sensitivity. This arrangement permits me to adjust the carbon block to a desired position and then complete the adjustment for 75 sensitivity without again moving the carbon block from the preferred position.

In addition to this feature, I prefer to provide extensions from the parts to be adjusted, passing through the case to points 80 where it or they may be reached and operated without opening the case, thus permitting the adjustment to be made after the parts are completely assembled and by means which may be graduated to the finest 85 lines. I prefer to pass the extensions through the case, but the same idea would be exhibited in a device in which the extensions did not so extend but the case was so constructed as to leave the parts accessible 90 for adjustment without opening the case, for instance if the case herein shown were so deep that the parts did not extend through it, but the aperture was sufficiently large for the insertion of a screw driver to turn said 95 extensions.

In the embodiment shown, 1 is the case of the instrument, preferably given a cup shape, with the edge threaded to receive the cover 2 which is pierced at 3 to permit the 100

passage of sound waves. The case 1 is apertured, preferably centrally, to receive the extensions of the carbon supporting parts. The carbon diaphragm 4 is held between the 5 cover and the case, resting upon the edge of the case and clamped thereto by the cover ring which is suitably shaped to perform that function. In the aperture in the case I first seat an insulator 5, of mica, hard rubber or other suitable substance, and through 10 that insulator, I prefer to extend a sleeved keeper 6, flanged on one side, threaded on the other end and provided with a nut 7 for locking it in position, the circuit arm or 15 terminal 8 being usually placed on said keeper, between the insulator and the nut and locked in position by turning down the nut. Then I provide a carbon block 9, preferably fastened to an extension 10, which is 20 threaded to turn in threads cut in the interior of the sleeved keeper 6, and provided with a lock nut 11 which may be turned down on the extended part and against the end of the keeper 6. The face of the carbon 25 block is recessed, preferably centrally as at 12, to receive the carbon contacts 13, in the form of polished balls of minute diameters, and to render the adjustment still more delicate, I prefer to extend the recess in 30 block 9 entirely through it and through its extension 10 and to mount therein a carbon post or pencil 14, with an extension 15, threaded in the aperture in the block extension 9 and provided with a lock 35 nut 16. The outer extremity may be provided with a slot or groove as shown, or any other means for conveniently turning it. Binding posts 17, 18 and lead wires 19, 20 40 are too well known to need particular description.

It will be noted that the extension 10 of block 9 and the extension 15 of the carbon pencil 14, both project beyond the case 1, so that they may be readily operated with- 45 out opening that case. The respective parts of the instrument having been assembled, and this may be done by unskilled labor, the skilled adjuster connects the instrument to his testing circuit, takes it in his hand and 50 turns in the extension 10 until the block 9 reaches the desired proximity to the dia- phragm 4 and locks it in position by turn- 55 ing down nut 11. Then he adjusts the posi- tion of the ball contacts by turning in the extension 15 of pencil 14—which acting against the carbons 13 will carry them against the face of the diaphragm 4, and having secured the sensitiveness desired, he turns down nut 16 and the instrument is 60 ready for use.

This, as will be noted, may be done while the instrument is actually in circuit, which renders it possible to adjust it much more perfectly as well as more quickly, since it 65 is not necessary to guess how much change

is required, take the instrument apart, make the change, put it together, try again, and perhaps again; but with it in hand the trial may be made, the change accomplished— 70 without breaking the circuit or other manipulation other than turning in or out the extensions which are ready to the finger for that purpose.

Then too, if by jar or other rough han- 75 dling, the adjustment is disturbed, or the use to which the instrument is to be put re- quires a different adjustment, such read- justment may be made as conveniently and quickly as the original adjustment and in 80 the same manner, by simply manipulating the extensions 10 and 15. In fact many ad- justments may be made by turning exten- 85 sion 10 alone, since that in carrying the block 9 inward or, outward, will also carry the carbon pencil 14 inward or outward and increase or decrease the pressure of the carbons upon the diaphragm, according to the direction of the movement.

So too, many adjustments may be made by simply projecting the carbon pencil 14, 90 or drawing it back, without altering the position of the block 9 and this may be done even when the extensions do not ex- tend through the case.

It will be manifest to any one of any 95 mechanical knowledge, that the forms of the instrumentalities employed may be varied almost at will without departing from the spirit of the idea, and I do not intend to be limited to the form or arrange- 100 ment shown, that being but one of the many which may be developed when the idea has been once made clear.

What I claim and desire to secure by Let- 105 ters-Patent, is:—

1. In a telephone instrument, a case, a diaphragm, a series of carbon particles con- 110 tacting with said diaphragm, a support for said carbon particles, in the form of a re- cessed block containing a carbon pencil lo- cated in the recess in said block, and an ex- 115 tension from said pencil projecting through the case and accessible from the outside thereof and adjustable inward or outward.

2. In a telephone instrument, a case, a diaphragm within the case, a carbon block 120 mounted within the case and provided with a central aperture and an extension project- ing through an aperture in the case, a keeper interposed between the said extension and 125 the case and insulated therefrom but threaded to the extension, a carbon pencil project- ing into the block recess and pro- 130 vided with an extension threaded in the block extension and projecting beyond the case, particles of carbon seated in the block recess and impinging upon the diaphragm and means for securing the extensions in varied positions, all combined substantially as set forth.

3. In a telephone instrument, a case, a diaphragm supported from said case, a recessed block also supported from said case, and provided with an adjustable carbon pencil located in said recess, a series of carbon particles also located in said recess but in front of the carbon pencil, and means for

advancing or drawing back said carbon pencil.

In testimony whereof, I have signed my 10 name to this specification this 4th day of December, 1916.

GASTON BOISSONNAULT.
